UNITED STATES PATENT OFFICE.

CHARLES A. FORD, OF NEWARK, NEW JERSEY.

PAPER BOX.

1,084,851.

Specification of Letters Patent. Patented Jan. 20, 1914.

Application filed July 25, 1913. Serial No. 781,149.

To all whom it may concern:

Be it known that I, CHARLES A. FORD, citizen of the United States, residing at Newark, in the county of Essex and State of New Jersey, have invented certain new and useful Improvements in Paper Boxes, of which the following is a specification.

The present invention relates to certain new and useful improvements in paper boxes or cartons of that general type which are adapted to be formed from a single folded blank of material, the primary object of the invention being to provide a carton which embodies novel features of construction whereby an interior shelf is provided for the support of the articles which are being packaged.

Further objects of the invention are to provide a folding box which securely locks together without the necessity for using any glue or adhesive, which provides ample space for printed matter which may be printed upon the interior thereof so as to form a circular when opened, and in which the printed matter is necessarily brought to the attention of the purchaser as he opens the box to obtain the articles packed therein.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a plan view of the blank from which the box is formed. Fig. 2 is a plan view showing the first step in folding the blank. Fig. 3 is a similar view showing the second step in folding the blank. Fig. 4 is a similar view showing the third step in folding the blank. Fig. 5 is a similar view showing the fourth step in folding the blank. Fig. 6 is a similar view showing the fifth step in folding the blank. Fig. 7 is a similar view showing the sixth step in folding the blank. Fig. 8 is a transverse sectional view through the folded box, on the line X—X of Fig. 7. Fig. 9 is a longitudinal sectional view through one end of the folded box, on the line Y—Y of Fig. 8. Fig. 10 is a top plan view of the folded box. Fig. 11 is a transverse sectional view showing a slight modification.

Corresponding and like parts are referred to in the following description and indicated in all the views of the drawings by the same reference characters.

This paper box or carton has been more especially designed for the packaging of thumb tacks, although the construction may also be advantageously employed for other articles of merchandise.

In describing the box certain parts of the blank will be arbitrarily designated as the top section, inner bottom section, outer bottom section, side sections, and end sections, although it will be understood that the box need not necessarily rest in any particular position, these terms being merely used to designate the relative positions of the parts.

The box is adapted to be formed from a single blank A of sheet material, such as shown by Fig. 1, the said blank being folded upon the various scorings *a* in forming the box.

The numeral 1 designates the top section of the box, 2 the inner bottom section of the box, and 3 the outer bottom section of the box, the said bottom sections being connected to the top section by the side sections 4. The end sections 5 are located at opposite ends of the top section 1 and are provided with the tuck flaps 6. The outer bottom section 3 is provided with a sealing flap 7, while the inner bottom section 2 carries an article supporting shelf 8. This shelf 8 is connected to the inner bottom section 2 by a suitable side web 9, and is provided at the free edge thereof with a sealing tongue 10.

The initial step in folding the blank to form the box consists in bending the article supporting shelf 8 upwardly over the inner bottom section 2 and inserting the sealing tongue 10 through the slit 11 which is formed in the blank A at a point adjacent the junction of the inner bottom section 2 and side section 4. (See Fig. 2). The articles of merchandise such as the thumb tacks B are applied to the supporting shelf 8 which is arranged within the interior of the box so as to be spaced from the top and bottom thereof, preferably extending substantially diagonally between opposite corners of the box, as indicated by Fig. 8. In this connection it will be noted that the side web or support 9 holds one edge of the shelf 8 away from the inner bottom section 2, while the engagement of the sealing tongue 10 with the slit 11 draws the opposite edge

2
of the shelf 8 toward the section 2. The blank is next folded along the successive longitudinal score lines *a* as indicated by Figs. 3, 4, 5 and 6. When the outer bottom section 3 is folded against the inner bottom section 2, as indicated by Fig. 5, the slit 12 at the junction of the section 3 and sealing flap 7 is brought into substantial registry with the before mentioned slit 11 and the sealing flap 10 inserted through the said slit 12. This sealing flap 7 is next bent along one side of the box, as indicated by Fig. 6, and the projecting sealing tongue 10 then folded around the free edge of the sealing flap and the free end thereof inserted through a slit 13 formed in the blank at substantially the junction between the top section 1 and side section 4. (See Figs. 7 and 8). It will thus be obvious that the sealing tongue 10 provides a positive locking element for holding the various sections of the box in proper position, and also for holding the article supporting shelf 8 in proper position within the interior of the box. The end flaps 5 may next be folded into position and the tuck flaps 6 at the extremities thereof inserted between the inner bottom section 2 and outer bottom section 3 so as to be frictionally engaged and held in position between the said members.

In order to open the box the sealing flap 10 must be first drawn out of the slit 13 and the blank unfolded in the reverse manner of that just described.

35 The inner face of the blank may receive any desired printed matter either in the nature of an advertisement or of instructions for using the articles packed in the box, and as the box is opened, this printed matter is necessarily brought directly to the attention of the purchaser.

When the box has been opened to the extent indicated by Fig. 2, the thumb tacks B, or other articles secured to the interior supporting shelf 8 are brought plainly into view and can be removed at the pleasure of the purchaser. The box when opened to this extent can be very advantageously used for displaying the thumb tacks or other articles 50 in an attractive manner, both the thumb tacks themselves and the printed matter upon the inner face of the blank being plainly in sight.

When the box is completely folded, as indicated by Fig. 10, the parts are all securely locked together so that the box can be subjected to rough handling without danger of opening up or coming apart. The thumb tacks B are also held securely in position within the interior of the box so that they will not be jostled around and the points thereof caused to project through the boxes when the boxes are being transported or handled.

45 A slight modification is shown in Fig. 11

in which the article supporting shelf 8^a is formed slightly wider and the side support 9^a therefor made slightly narrower so as to fit closely against the side 4 of the box. With this construction the article supporting shelf 8^a extends diagonally across the interior of the box so as to connect opposite corners thereof. This construction may be found advantageous for the packaging of certain articles.

Having thus described the invention, what I claim as new and desire to secure by Letters Patent, is:—

1. A paper box formed from a single folded blank having a sealing tongue at one end thereof, said blank being bent upon a series of successive folds to provide inclosing sides and portions of the blank being caused to overlap on one side of the box, said overlapping portions being provided with corresponding slits adapted to receive the sealing tongue, and an additional slit being provided in another side of the box to receive the free end of the sealing tongue, the said sealing tongue serving to lock the blank in a folded position.

2. A paper box formed from a single folded blank having an integral extension at one end thereof adapted to be folded within the interior of the box to provide an article supporting shelf, said integral extension having a sealing tongue at the end thereof and the blank being adapted to be bent upon a series of successive folds to provide inclosing walls surrounding the article supporting shelf, portions of the blank being caused to overlap upon one side of the box, and said overlapping portions being formed with corresponding slits adapted to receive the sealing tongue.

3. A paper box formed from a single folded blank and including an inner article supporting shelf provided with a sealing tongue, portions of the blank being caused to overlap in forming the box and said overlapping portions being provided with corresponding slits adapted to receive the sealing tongue, an additional slit being formed in the opposite side of the box to receive the extremity of the sealing tongue, the said sealing tongue serving to retain the article supporting shelf in proper position and also to lock the blank in a folded position.

4. A paper box formed from a single folded blank which has an interior article supporting shelf at one end thereof and a sealing flap at the opposite end thereof, the article supporting shelf being provided with a sealing tongue and portions of the blank being caused to overlap in forming the box, said overlapping portions being formed with corresponding slits adapted to receive the sealing tongue, and a slit being formed in the opposite side of the

box to receive the extremity of the sealing tongue after it has been folded over the sealing flap.

5. A paper box formed from a single folded blank having a plurality of slits therein and formed with a top section, side sections, an inner bottom section, an outer bottom section, and an article supporting shelf at one side of the inner bottom section, a sealing tongue being provided at the free edge of the article supporting shelf and the said sealing tongue being adapted to be threaded through the slits of the blank to lock the blank in a folded position.

10 15 6. A paper box formed from a single folded blank, said blank having a plurality of slits therein and being formed with a top section, side sections, an inner bottom section, an outer bottom section, end sections

provided with tuck flaps, a sealing flap at 20 the free edge of the outer bottom section, and an article supporting shelf at the free edge of the inner bottom section, the free edge of the article supporting shelf being formed with a sealing tongue adapted to be 25 threaded through the before mentioned slits and folded around the sealing flap to lock the blank in a folded position, the tuck flaps of the end sections being inserted between the superposed inner and outer bottom sections. 30

In testimony whereof I affix my signature in presence of two witnesses.

CHARLES A. FORD.
